(57) CLAIM

The ornamental design for a digital grill, as shown and described herein.

DESCRIPTION

FIG. 1 is a front, left side perspective view of the digital grill of the invention.

FIG. 2 is a front elevation view of the digital grill of the invention.

FIG. 3 is a rear elevation view of the digital grill of the invention.

FIG. 4 is a left side view of the digital grill of the invention.

FIG. 5 is a right side view of the digital grill of the invention.

FIG. 6 is a top view of the digital grill of the invention.

FIG. 7 is a bottom view of the digital grill of the invention; and,

FIG. 8 is a front, right side perspective view of the digital grill of the invention.

The broken lines in the drawings are for environmental illustration only and form no part of the claimed design.
